CLAIM

The ornamental design for a two piece door unit for a
vehicle, as shown and described.

DESCRIPTION

FIG. 1 is a perspective view taken from the right side of
a two-piece door unit for a vehicle showing my new
design in open condition;

FIG. 2 is a front perspective view thereof;
The broken lines in the drawings are for illustrative
purposes only.

FIG. 1**FIG. 2**

FIG. 3

FIG. 4
